TEXTILE APPARATUS

Reginald Henry John Riley, Ralph Ashton, and Harold Livesey, Spondon, near Derby, England, assignors to Celanese Corporation of America, a corporation of Delaware

Application August 20, 1935, Serial No. 36,942
In Great Britain September 3, 1934

7 Claims. (Cl. 118—62)

This invention relates to textile apparatus, and particularly to cap-spinning apparatus for the twisting and winding of threads, the object of the invention being to extend the usefulness of 5 cap-spinning devices both as to speed of operation and size of package to be formed by such devices.

The cap of a cap-spinning device is carried by the upper end of a stationary spindle extending 10 upwardly through the axis of the bobbin or other package support surrounding the spindle, the cap depending about the package support so that its lower edge forms a guide to conduct the thread to the support. Traversing of the package support 15 along the cap spindle causes the thread, which has been twisted by its rotation about the cap after leaving a balloon guide disposed some distance above the cap, to be traversed along the support by the cap edge. Winding of the thread 20 takes place at the rate at which the thread is delivered to the balloon guide, the revolutions of the package support in excess of those necessary to effect the winding serving to impart twist to the thread.

25 Since only the package support rotates, the cap-spinning device is capable of high rates of twisting, and is particularly serviceable for applying twist to threads delivered at a high rate, as, for example, in the production of artificial silk 30 threads by the dry-spinning operation. It has been found, however, that with high package speeds and/or with large package supports vibration is sometimes set up in the cap, no doubt due to the necessary disposition of the cap at 35 some distance above the point at which the cap spindle is secured to its supporting rail. The present invention reduces this tendency to vibration, and its consequent interference with the twisting and winding operation.

40 According to the invention the cap is provided with damping means comprising a mass capable of limited movement with respect to the cap.

The movement of such a mass may be limited 45 by the boundaries of a cavity in the cap and in which the mass moves, and/or by spring means. Such spring means may also serve to secure the mass to the cap.

In the accompanying drawing a number of cap- 50 spinning devices in accordance with the present invention are illustrated.

Figure 1 shows an elevation in section of a cap- 55 spinning device in which the mass is located in a cavity in the head of the cap.

Figure 2 illustrates a device in which the mass

is in the form of an annulus anchored to the neck of the cap by means of springs.

Figure 3 is a plan view of Figure 2.

Figure 4 shows a modified form of the device shown in Figures 2 and 3.

Figure 5 shows a further form of device in which the mass is in the form of a weight arranged eccentrically with respect to the neck of the cap.

Figure 6 is a plan view of the device shown in Fig. 5.

Referring to Figure 1, a cap 7 in operation is supported on the spindle 8 fitting into the tapered bore in the boss 9. The cap is provided with a false top 10 which forms the cavity 11 in which 15 iron filings, sand or other hard granular material 12 is placed.

Referring to Figures 2 and 3, the cap 13 has anchored to the neck 14 thereof by springs 15 an annulus 16, for example of lead.

Referring to Figure 4, anchored to the top of the cap 13 by the springs 17 there is an annulus 18.

Referring to Figures 5 and 6, the cap 13 has anchored to the neck 14 thereof the weight 19 by an extension of the spring 20.

What we claim and desire to secure by Letters Patent is:—

1. A cap spinning device provided with damping means said device comprising a non-rotary cap, a mass located in proximity to the head of 30 said cap, and means for retaining said mass on said cap, said means permitting a limited movement of said mass with respect to the axis of said cap and resisting such movement.

2. A cap spinning device having a cavity located 35 in the head of the non-rotary cap adapted to receive granular material and to permit limited movement of said material with respect to the axis of the cap.

3. A cap spinning device provided with damping means comprising a mass located in proximity to the head of the non-rotary cap and spring means securing the mass to the cap and permitting limited movement of said mass with respect to the axis of the cap.

4. A cap spinning device provided with damping means comprising a metal annulus located in proximity to the head of the non-rotary cap and arranged concentrically with respect to the axis of the cap and spring means anchoring said annulus to said cap and permitting limited movement of said annulus with respect to the axis of the cap.

5. A cap spinning device comprising a non-rotary cap provided with a cavity in the head 55

thereof and a mass that is located in said cavity whereby said mass is permitted limited movement with respect to the axis of the cap and such movement is resisted by the interior surface of said cavity.

5 6. A cap spinning device comprising a non-rotary cap provided with a cavity on the head thereof and a mass of granular material that is located in said cavity, whereby said mass is permitted limited movement with respect to the axis of the cap, and such movement is resisted by the interior surface of said cavity.

7. A cap spinning device provided with damping means comprising a non-rotary cap, a mass located in proximity to the head of said cap and spring means for retaining said mass on said cap, said spring means permitting a limited movement of said mass with respect to the axis of the cap and resisting such movement.

REGINALD HENRY JOHN RILEY.

RALPH ASHTON.

HAROLD LIVESEY.
